(No Model.)

P. H. AINSWORTH.

WIRE STRETCHER.

No. 358,138.

Patented Feb. 22, 1887.

FIG. 1.

FIG. 2.

ATTEST.

J. Henry Kaiser.
Harry L. Amer.

INVENTOR.

P. H. Ainsworth

UNITED STATES PATENT OFFICE.

PHINEAS HARDAMAN AINSWORTH, OF CANEY, TEXAS.

WIRE-STRETCHER.

SPECIFICATION forming part of Letters Patent No. 358,138, dated February 22, 1887.

Application filed September 29, 1886. Serial No. 214,872. (No model.)

To all whom it may concern:

Be it known that I, PHINEAS HARDAMAN AINSWORTH, a citizen of the United States, residing at Caney, in the county of Matagorda, 5 State of Texas, have invented a new and useful Machine for Stretching, Building, and Repairing Wire Fences, of which the following is a specification.

My invention relates to improvements in wire-stretching machines; and it consists of the mechanism hereinafter set forth and claimed, having for its objects the stretching of wire in building new fences and the splicing of broken or slack wire in old fences, in such a manner 15 that no slack is left when the said splice has been made. I attain these objects by the mechanism illustrated in the accompanying drawings, in which—

Figure 1 is a view of the machine, shown after 20 a splice has been made in broken wire and before it has been removed from the said wire. Fig. 2 is an enlarged view of that part of the mechanism which I shall designate as the "center holder," showing it with clamp upraised 25 and the two ends of a broken wire placed in its slots and in position to be clamped and held while making splice.

Similar letters refer to similar parts throughout both views.

30 My machine is made of cast or malleable iron and of any convenient size.

A is a projecting rod fitting into the semi-circular frame B, and is used as a side rest to assist in supporting the weight of the machine 35 when it is in position for splicing or stretching. It is shown broken in the drawings, for convenience in making said drawings. During the operation of splicing it is not intended to be always perpendicular, but may incline at 40 any convenient angle, in accordance with the height of the wire being spliced.

C is a center holder made solid with the frame B, and to it is fitted the clamp D and loop E.

45 F is a rope winding and unwinding on the drum G, secured to the movable clamp I, and passing over the stationary pulley H.

N is a lever for revolving drum G, and M a spring-pawl acting on the ratchet P and holding drum and rope taut, when desired.

O O are two fence-posts, and Q a wire running between them.

R is a chain attached to the end of rod A, and is used to fasten the machine to a post in making new fence. This is done by wrapping 55 the said chain around both the post and rod A and securing it with the hook at the end.

L is an eccentric cam, made stationary; and K is an eccentric cam forming part of the movable clamp I.

Having described and enumerated the various parts of my machine, the manner of its operation is as follows: Supposing the wire Q between posts O O is broken and a splice desired, the machine is applied by catching one 65 end of the broken wire in the stationary clamp L and the other in the movable clamp I, the two ends being caught far enough back to allow a sufficient length of each in the semicircle to make the splice. The two ends of the 70 wire being caught in the manner described, the drum G (operated by lever N) is revolved, and by means of rope F, pulley H, and movable clamp I the wire is stretched until taut, and is held so by the spring-pawl M and ratchet P. 75 The two ends of broken wire T and S are then drawn as tight between the clamps L and I as can be done with the fingers, and are placed in the slots V. The clamp D is brought down over them and secured by loop E. By this 80 means the ends are held firmly in the center holder, C, and the splice is made by twisting the ends T and S, as shown in the drawings. The machine is next removed, and the wire remains taut without any slack.

In case a wire is found slack and it is desired to tighten it, the wire is cut and a splice is made in the same way as above.

In building a new fence the stretcher is fastened to the post by the chain R in the manner described, and the wire is then caught in the clamp I and drawn tight by means of the drum and rope, as has been described. By the spring-pawl and ratchet it is held tight until it can be fastened to the post in the usual manner.

What I claim as my invention, and desire to secure by Letters Patent, is—

1. In a wire stretching and splicing implement, the combination of a frame having two arms, one carrying a fixed clamp and the other 100

a roller, a windlass mounted on said frame having a rope passing over said roller, a clamp on the end of said rope, and a central clamp between the arms of the frame to hold the wires 5 while being twisted, substantially as set forth.

2. In combination with a frame having two arms, one carrying a fixed clamp and the other a roller, a windlass mounted on said frame having a rope passing over said roller and 10 adapted to be fixed to an end of wire, and a central clamp consisting of a rigid bar on the frame between its arms, a notched clamp pivoted thereon, and a ring for retaining the clamp, substantially as set forth.

3. The combined wire stretching and splicing 15 implement, consisting of the combination of a frame having two arms, carrying one a fixed and the other a movable clamp, a rod fixed to said frame, and a chain for fixing said rod and frame to a post, substantially as set 20 forth.

PHINEAS HARDAMAN AINSWORTH.
